UNITED STATES PATENT OFFICE.

ADOLPH RICHTER, OF NEW YORK, N. Y.

UPRIGHT-PIANO ACTION.

SPECIFICATION forming part of Letters Patent No. 408,852, dated August 13, 1889.

Application filed January 25, 1889. Serial No. 297,536. (No model.)

To all whom it may concern:

Be it known that I, ADOLPH RICHTER, of the city, county, and State of New York, a citizen of the United States, have invented certain new and useful Improvements in Upright-Piano Actions, of which the following is a specification.

The object of my invention is to provide a piano-action having a contrivance for throwing back the hammer after the same has struck the string, which contrivance can be adjusted to throw the hammer backward more or less rapidly.

The invention consists in the construction and combination of parts and details, as will be fully described and set forth hereinafter, and finally pointed out in the claims.

In the accompanying drawings, Figures 1 and 2 are vertical transverse sectional views of piano-actions provided with my improvement, the parts being shown in different positions.

Similar letters of reference indicate corresponding parts.

25 The hammer A is secured to the hammer-butt B, pivoted to the hammer-rail C in the usual manner, and when at rest the hammer rests upon the hammer-rest D. The hammer is operated in the usual manner by the jack

30 E, that acts on the hammer-butt, and is pivoted to the jack bed or lever F, which in turn is pivoted to the jack-rail G. The damper-lever H and back-catch J are of the usual construction. On a rail K a lever L is pivoted

35 to hang downward, and the swinging end of said lever is felted and adapted to act on that edge of the hammer-butt facing the string I. The lever L is provided with a lug M, having an offset M', on which a collar or other pro-

40 jection N can act that is secured to the reciprocating rod O, the lower end of which is connected with a frame P, mounted on the jack bed or lever F, and vertically adjustable on the same by means of a screw Q, the head R

45 of which is cogged or toothed on its rim, thus permitting of inserting a rack for engagement with said teeth for the purpose of turning the screw, and thus adjusting the frame P, and thereby adjusting the rod O and its

50 collar N in relation to the lug M on the lever L. The upper end of the rod O is guided in

an aperture or notch of the plate S on the rail K.

The operation is as follows: When the parts are in the position of rest, as in Fig. 1, 55 and the key is depressed, the hammer A is thrown toward the string I, as indicated by the arrow x' in Fig. 1. As the jack bed or lever F moves upward, the rod O also moves upward, and its collar or projection N, striking the offset M' of the lug M, throws the lower end of the lever L in the direction of the arrow x², Fig. 1, and said lower end of the lever L, acting on the hammer-butt B, swings the hammer in the direction from the strings— 65 that is, throws the hammer back without the use of springs or analogous device, and operates positively. The rod O can easily be so adjusted as to cause the lever L to throw the hammer back sooner or later, as may be 70 necessary.

Having thus described my invention, I claim as new and desire to secure by Letters Patent—

1. In a piano-action, the combination, with a hammer and jack bed or lever, of a pivoted 75 lever acting on the hammer and operated from the jack-lever, substantially as set forth.

2. In a piano-action, the combination, with a hammer and jack, of a pivoted lever adjacent to the hammer, and a rod operated from 80 the jack-lever and acting on said lever, substantially as set forth.

3. In a piano-action, the combination, with a hammer and jack, of a lever pivoted adjacent to the hammer, and an adjustable rod 85 connected with the jack-lever and serving to operate said lever, substantially as set forth.

4. In a piano-action the combination, with a hammer and jack, of a lever pivoted adjacent to the hammer, a projection on said lever, and a rod connected with a jack-lever 90 and acting on said projection, substantially as set forth.

5. In a piano-action, the combination, with a hammer and jack, of a lever pivoted adjacent to the hammer, a lug on said lever, a rod acting on said lug, and an adjustable frame 95 on the jack-lever, with which frame said rod is connected, substantially as set forth.

6. In a piano-action, the combination, with 100 a hammer and jack, of a lever pivoted adjacent to the hammer, a lug on said hammer, a

rod having a projection that can act on said lug, a frame mounted adjustably on the jack-lever, with which frame said rod is connected, and a screw for adjusting said frame, substantially as set forth.

7. In a piano-action, the combination, with a hammer and jack, of a lever pivoted adjacent to the hammer, a rod acting on said lever, a frame on the jack-lever, to which frame said rod is pivoted, a screw for adjusting said

frame on the jack-lever, and a cogged head on said screw, substantially as set forth.

In testimony that I claim the foregoing as my invention I have signed my name in presence of two subscribing witnesses.

ADOLPH RICHTER.
